UNITED STATES PATENT OFFICE.

ESTHER B. FINK, OF CHARLESTON, WEST VIRGINIA.

BUTTON-CLASP.

1,342,161.

Specification of Letters Patent. Patented June 1, 1920.

Application filed March 23, 1920. Serial No. 368,091.

To all whom it may concern:

Be it known that I, ESTHER B. FINK, a citizen of the United States, residing at Charleston, in the county of Kanawha and 5 State of West Virginia, have invented a new and useful Button-Clasp, of which the following is a specification.

The device forming the subject matter of this application is a separable fastener, and 10 the invention aims to provide novel means whereby the edges of a garment may be held together without necessitating the making of button holes.

With the above and other objects in view, 15 which will appear as the description proceeds, the invention resides in the combination and arrangement of parts and in the details of construction hereinafter described and claimed, it being understood 20 that, within the scope of what is claimed, changes in the precise embodiment of the invention shown can be made without departing from the spirit of the invention.

In the accompanying drawings:—

25 Figure 1 shows in section, on a greatly enlarged scale, a device constructed in accordance with the invention; Fig. 2 is a plan showing the main member of the button; and Fig. 3 is a plan showing the auxiliary member of the button.

30 In carrying out the invention there is provided a main member 1 including a body 2 which may be made of bone, wood, celluloid or any other material commonly used 35 in the making of a button. The body 2 has holes 3, adapted to receive the attaching thread, and of these holes there may be any number. Four holes are supplied in the present instance, but this detail is not mandatory. On its inner side, the body 2 of the 40 button is provided with a recess 4 wherein a back plate 5, which may be made of metal, is seated and secured. The back plate 5 has openings 6 coinciding with the 45 openings 3 of the body 2. About the edges of the openings 6, the back plate 5 is supplied with flanges 7 extended into the holes 3 of the body 2, and engaged in the body 2 within the contour of the holes, thereby to anchor the back plate 5 in the recess 4. A 50 resilient stub 8 of any desired construction projects rearwardly from the back plate 5 and is secured thereto.

The device includes an auxiliary member 9 made of metal or any other suitable material, the member 9 comprising a flat

outer part 10 and a concaved inner part 11, there being openings 12 in the part 10 disposed opposite to openings 14 in the part 11. There may be any number of the openings 12 and 14. Four of them are shown in the present instance, but this detail may be departed from. A thread 15 is passed through the openings 3 of the body 2 and through the openings 6 of the back plate 5, 60 the thread serving to hold the main member 1 on one piece 17 of material, the stud 8 projecting through the material. The inner part 11 of the auxiliary member 9 is placed against another piece of material 70 indicated at 18 and is attached thereto by threads 16, extended through the openings 12 and 14 and around the edge of the part 9. The outer part 10 of the member 9 is supplied with an opening 25 in which the 75 resilient stud 8 is adapted to be engaged, and it is clear that when the stud is engaged in the opening, as aforesaid, the pieces 17 and 18 of material will be held together. 80

The device forming the subject matter of this application obviates the necessity of making button holes in a garment or the like, and will be found to be thoroughly efficient for the ends in view. 85

Having thus described the invention, what is claimed is:—

1. In a device of the class described, a main member comprising a body; a back plate provided with a resilient stud, the 90 back plate being secured to the body, the body and the back plate having co-operating thread-receiving openings; and an auxiliary member having an aperture receiving the stud. 95

2. In a device of the class described, a main member comprising a body; a back plate provided with a resilient stud, the back plate being secured to the body, the body and the back plate having co-operating 100 thread-receiving openings; and an auxiliary member including a flat outer part and a concaved inner part, both of said parts having thread-receiving openings, and the outer part having an aperture receiving the 105 stud.

3. In a device of the class described, a main member comprising a body having openings; a back plate having a resilient stud, the back plate having openings co-operating with the openings of the body, there being flanges on the back plate adj-

cent to the openings thereof, the flanges being extended into the openings of the body and being prolonged outwardly and anchored in the body within the contour of the openings of the body; and an auxiliary member having an opening receiving the stud.

In testimony that I claim the foregoing as my own, I have hereto affixed my signature in the presence of two witnesses.

ESTHER B. FINK.
